UNITED STATES PATENT OFFICE.

HAZEL D. AMOS, OF SARGENT, NEBRASKA.

CURTAIN STRETCHER.

Application filed March 1, 1928. Serial No. 258,278.

The invention relates to a curtain stretcher.

The object of the present invention is to provide a simple, practical and efficient curtain stretcher of strong, durable and comparatively inexpensive construction adapted for hanging and stretching curtains at a window and capable of ready adjustment to fit windows of different sizes and to support and stretch curtains of different dimensions.

10 A further object of the invention is to provide a curtain stretcher of this character adapted to stretch a curtain to the desired tension and capable of holding the same at such tension and of maintaining a curtain in 15 a smooth condition during the entire time the same is hung or supported at a window.

It is also an object of the invention to provide a curtain stretcher of this character equipped with means for supporting a curtain the desired distance from the window 20 frame and capable of also supporting draperies and hangings.

With these and other objects in view, the invention consists in the construction and 25 novel combination and arrangement of parts hereinafter described, illustrated in the accompanying drawings and set forth in the claims hereto appended, it being understood that various changes in the form, size and 30 minor details of construction, within the scope of the claims, may be resorted to without departing from the spirit of the invention or sacrificing any of the advantages thereof.

In the drawings:

35 Fig. 1 is an elevation of a curtain stretcher constructed in accordance with this invention and shown applied to a window.

Fig. 2 is an elevation of one of the side members of the curtain stretcher.

40 Fig. 3 is a horizontal sectional view of a portion of the curtain stretcher.

Fig. 4 is a detail view of the lower end portion of one of the side members, partly in section.

45 In the accompanying drawings, in which is illustrated the preferred embodiment of the invention, the curtain stretcher comprises in its construction side rods composed of upper and lower tubular telescoping sections 1 and 50 2, rigidly clamped in their adjustment by a set screw 3 which is preferably mounted in a band or collar 4 surrounding the upper end of the lower tubular section 2, as clearly illustrated in Fig. 2 of the drawings. The upper 55 and lower sections of the side rods are provided at their outer ends with horizontal

arms 5 and 6 located at the top and bottom of the curtain stretcher and preferably consisting of rods bent at right angles at one end at 7 and secured in the tubular sections 1 and 2 of the side rods. The upper and lower horizontal arms 5 and 6 are provided with terminal prongs 8 diverging rearwardly and having their outer terminals bent at right angles to form tapering projections 9 which are 65 preferably in the form of blades for engaging a window frame 10 at the top thereof and beneath the window sill 11. The projections or blades firmly engage the window frame and enable the side members to be rigidly secured to the said window frame.

The side members comprise the telescoping sections 1 and 2, the horizontal upper and lower arms 5 and 6, and horizontal supporting plates 12 and 13 located at the upper and lower portions of the window and arranged in planes at right angles to the plane of the window and provided with a plurality of openings 14 for the reception of upper and lower horizontal stretcher rods or bars composed of telescoping sections 15 and 16. The telescoping sections 15 and 16 are provided at their outer ends with projections 17 preferably formed by pins and adapted to be passed through recesses 18 forming extensions of the openings 14 at the top thereof. After the ends of the horizontal stretcher rods are arranged in the openings 14 and the projections passed through the recess 18, the rods are partially rotated to carry the projections 17 away from the recesses 18. This will retain the stretcher rods in the openings of the upper and lower horizontal supporting plates. The horizontal supporting plates extend in advance and in rear of the side rods, 95 as clearly shown in Fig. 2 of the drawing, and each of the projecting portions of the horizontal plates is preferably provided with a pair of openings 14, making four openings 14 in each of the horizontal supporting plates, 100 but the number of openings may be varied, as will be readily understood.

The upper horizontal supporting plates are preferably rigid with the sections 1 and are provided with sleeves 19 arranged on the upper sections 1 and rigidly secured to the same. The lower horizontal supporting plates are provided with sleeves 20 slidable on the lower sections 2 to permit an adjustment of the lower horizontal supporting plates to 110 arrange the stretcher rods the desired distance apart to suit the size of the curtain to

be hung and stretched. The lower horizontal supporting plates are secured in their adjustment by set screws 21 mounted on rings or collars 22 and extending through the horizontal supporting plates 13. The rings or collars are slidably arranged on the lower sections 2 of the side rods and the lower sections 2 are provided with the clamping nuts 23 which are preferably in the form of winged thumb nuts. The thumb nuts are adapted to be tightened and the set screws will cause the sleeves 20 of the lower horizontal supporting plates to bind against the lower tubular sections and firmly clamp the lower supporting plates in their vertical adjustment on the side rods.

In practice, the horizontal stretcher rods are passed through hems in the top and bottom of the curtain to be hung and stretched, and after the curtain is arranged on the stretcher rods the latter are placed in the desired openings of the upper and lower horizontal supporting plates. The lower supporting plates are then moved downwardly on the side rods to stretch the curtain to the desired tension and are clamped in such adjustment. This will maintain a curtain in a smooth stretched condition at the window and the desired distance from the same. Other rods similar to the stretcher rods may be placed in the openings of the upper supporting plates for supporting draperies, hangings and the like.

What is claimed is:

1. A curtain stretcher comprising vertical side rods designed to be located at opposite sides of a window and provided at their ends with means for securing them to a window frame, parallel horizontal upper and lower supports projecting forwardly and rearwardly from the side rods and provided with sleeves embracing the side rods, the sleeves

of the upper supports being fixed to the side rods, and collars slidable on the side rods and provided with set screws piercing the lower supports and securing the same in vertical adjustment on the side rods, and stretcher bars carried by the upper and lower supports and extending across the space between the side rods and adjustable to points in advance and in rear of the side rods.

2. A curtain stretcher adjustable vertically and laterally to vary the length and width of the curtain stretcher and comprising vertical side rods having telescoping sections and provided at their upper and lower ends with horizontal arms having terminal prongs, the latter being provided with means for engaging a window frame, upper and lower parallel supporting plates mounted on the sections of the side rods and provided with openings, and transverse stretcher bars composed of telescoping sections and extending across the space between the side rods and secured in the openings of the supporting plates.

3. A curtain stretcher adjustable vertically and laterally to vary the length and width of the curtain stretcher and comprising upper and lower telescoping side rods provided at their ends with means for engaging a window frame, parallel upper and lower horizontal supporting plates carried by the side rods, the lower supporting plates being provided with sleeves, collars arranged on the side rods and provided with screws piercing the lower supporting plates, clamping nuts mounted on the screws and engaging the said lower supporting plates for securing the same in vertical adjustment, and stretcher bars carried by the supporting plates and composed of telescoping sections.

In testimony whereof I have hereunto set my hand.

HAZEL D. AMOS.
